[57] CLAIM

The ornamental design for an ink stylus pen, as shown and described.

DESCRIPTION

FIG. 1 is a top, right front perspective view of an ink stylus pen showing my new design;

FIG. 2 is a top, right front perspective view in an exploded condition;

FIG. 3 is a typical side elevational view of the pen body, with the cap member removed for convenience of illustration;

FIG. 4 is a right side elevational view of FIG. 1;

FIG. 5 is a rear elevational view of FIG. 1;

FIG. 6 is a front elevational view of FIG. 1;

FIG. 7 is a top plan view of FIG. 2 showing the writing tip;

FIG. 8 is a bottom plan view of the cap member, with the pen body removed for convenience of illustration;

FIG. 9 is a top plan view of FIG. 8; and,

FIG. 10 is a top, right front perspective view of a second embodiment of my design of FIG. 1.
